CLAIM

The ornamental design for a beach tent, as shown and described.

DESCRIPTION

FIG. 1 is a front perspective view of a beach tent, showing my new design;
FIG. 2 is a rear perspective view thereof;
FIG. 3 is a front view thereof;
FIG. 4 is a rear view thereof;
FIG. 5 is its enlarged left plan view;
FIG. 6 is its enlarged right plan view;
FIG. 7 is a top view thereof;
FIG. 8 is a bottom view thereof; and,
FIG. 9 is an enlarged detail view of area 9 in FIG. 2.
The dash-dot-dash broken lines encircling the enlarged views are for annotative purposes only and form no part of the claim thereof.

1 Claim, 9 Drawing Sheets
